UNITED STATES PATENT OFFICE.

THOMAS L. MELLICK, OF PLAINFIELD, NEW JERSEY.

LEAD-PENCIL.

1,224,769.

Specification of Letters Patent.

Patented May 1, 1917.

Application filed July 26, 1916. Serial No. 111,464.

To all whom it may concern:

Be it known that I, THOMAS L. MELLICK, a citizen of the United States, residing at Plainfield, in the county of Union and State 5 of New Jersey, have invented new and useful Improvements in Lead-Pencils, of which the following is a specification.

This invention relates to an improvement in lead pencils and its object is to provide an 10 indelible lead pencil with means of simple, efficient and practical character for insuring a continuous and uniform supply of moisture to the point of the pencil in order that the lines may be fixed as they are made 15 by the pencil.

A preferred embodiment of the invention is shown in the accompanying drawings wherein:—

Figure 1 is an elevation of the improved pencil;

Fig. 2 is a longitudinal sectional view thereof on an enlarged scale, and

Fig. 3 is a cross-sectional view thereof.

Similar characters of reference designate 25 corresponding parts throughout the several views.

The wooden stock 1 of the pencil is provided with a stick of lead 2 in the usual manner and is further provided with a 30 longitudinal bore extending from end to end thereof, parallel to the lead, in which is fitted a wick 3 whose diameter is relatively small, in practice about one-third the diameter of the stick of lead 2.

The pencil has at its butt or unsharpened end a reservoir 4 filled with spongy or absorbent material 5 which is saturated with suitable liquid, *e. g.* water, the reservoir being open adjacent the end of the pencil 40 and the wick 3 conveying the moisture from said reservoir to the sharpened end of the pencil. The moisture exudes from the exposed end of the wick 3 upon the tapered surface of the wood 1 and covers the exposed end of the lead stick 2.

The moisture is continuously delivered by the wick 3 at a uniform rate, and is applied to the exposed end of the lead in a sufficient degree to insure the permanence of the lines

made by the pencil but not in a sufficient degree to interfere with the convenient use of the pencil or to cause the lines to "run".

The pencil is sharpened in the ordinary manner, the wick being cut away with the wood and the lead.

The reservoir 4 may be constructed and applied to the butt end of the pencil in a suitable manner. However, it is preferably formed as a separate attachment and is provided with an enlarged extended cylindrical socket-piece which closely fits over the end of the pencil and adjacent the reservoir provides an annular shoulder 7 between which and the end of the pencil a packing-ring or gasket 8 is interposed for 65 the purpose of preventing leakage of the liquid with which the material 5 is saturated.

The outer end of the reservoir 4 is closed by a cap 9, which is preferably threaded into the end of the reservoir in order that it 70 may be readily removed when the material 5 or the liquid with which said material is saturated is to be renewed.

When not in use a shield or guard 10 may be fitted over the sharpened end of the pencil, both to protect the lead against breakage and to cover the exposed end of the wick 3 and thereby prevent evaporation of the liquid taken up by said wick.

The stock of the pencil may be of any 80 desired or approved construction, that known, resembling the stock of any ordinary pencil in that it is made in mating half sections which are secured together by glue or cement in the well known manner 85 and have complementary recesses which provide the bores for the stick of lead 2 and the wick 3.

I claim:—

1. A lead pencil comprising a wooden 90 stock inclosing a stick of lead and having an internal bore extending from end to end thereof parallel to the stick of lead, and a wick occupying the bore throughout its length.

2. A lead pencil comprising a wooden 95 stock inclosing a stick of lead and having an internal bore extending from end to end

thereof parallel to the stick of lead and a wick occupying the bore throughout its length in combination with a reservoir adapted to fit upon one end of said stock 5 and inclose an absorbent material saturated with moisture for transmission by said wick to the pointed end of the pencil.

Copies of this patent may be obtained for five cents each, by addressing the "Commissioner of Patents, Washington, D. C."

In testimony whereof I have hereunto set my hand in presence of two subscribing witnesses.

THOMAS L. MELLICK.
